UNITED STATES PATENT OFFICE.

MATTHIAS A. BECK, OF MILWAUKEE, WISCONSIN, ASSIGNOR TO MILWAUKEE ELECTRIC CRANE & MFG. CO., INCORPORATED, OF MILLBROOK, NEW YORK, A CORPORATION OF NEW YORK.

SAFETY-LIMIT SWITCH FOR ELECTRIC HOISTS.

Application filed January 12, 1920. Serial No. 350,762.

To all whom it may concern:

Be it known that I, MATTHIAS A. BECK, a citizen of the United States, residing at Milwaukee, in the county of Milwaukee and 5 State of Wisconsin, have invented certain new and useful Improvements in Safety-Limit Switches for Electric Hoists, of which the following is a specification, reference being had to the accompanying drawing, 10 forming a part thereof.

The main objects of this invention are to automatically open the circuit of an electric crane or hoist and thus prevent accidents and injury to the hoisting apparatus and 15 attendants by overwinding of the hoisting cable or elevation of the load beyond a certain limit; to automatically close and restore the hoisting circuit to operative condition when the load is lowered from the 20 safety limit; to prevent vibration of the crane or hoisting apparatus on which the limit switch is mounted from releasing the movable member of the switch; and generally to improve the construction and 25 operation of switches of this class.

The invention consists in the construction, arrangement and combination of parts as hereinafter particularly described and pointed out in the claims.

30 In the accompanying drawing like characters designate the same parts in the several figures.

Figure 1 is a section on the line 1—1, Fig. 2, of a safety-limit switch embodying the invention; Fig. 2 is a section of the 35 switch on the line 2—2, Fig. 1; and Fig. 3 is a diagram illustrating the circuit connections of the switch as applied to a typical electric crane or hoist.

40 Referring to Figs. 1 and 2, the switch comprises a case 1, provided with a removable cover 2, one or more relatively fixed contact members and one or more movable contact members, enclosed by the case.

45 In the present case a double break switch is shown, having two fixed and two movable contact members. Each fixed contact member comprises a carbon block 4, fastened with an interposed insulating block 5 to one side 50 of the case 1. Each movable contact member comprises a metal spring 6, fastened to and insulated from a metal plate or support 7, which is pivotally mounted on a pin 8.

The support 7 is formed or provided with 55 an arm 9 connected with the case by a spring 10 which tends to shift the springs 6 out of engagement with the blocks 4. The cylindrical hub of the plate or support 7 through which the pivot pin 8 passes, is formed with 60 a notch and radial shoulder 11 and with a lug or projection 12, having a face radial to the pivot pin.

The case 1 is provided with an insulating lining 14, around the contact pieces 4 and 65 6, and between the two fixed contact blocks or pieces 4 an insulating partition 15 is interposed, to prevent injury to the switch from arcing.

A rocker shaft 17 is supported by bearings 70 in the case 2 parallel with and adjacent to the pivot pin 8 of the movable contact member. On the shaft 17 within the case, is pivotally mounted a pawl or detent 18, adapted by engagement with the shoulder 75 11 to releasably hold the contact springs 6 in engagement with the contact blocks 4. At the end opposite that which engages with the shoulder 11, the pawl or detent 18 is formed with a lug or projection 19, having a face 80 radial to the shaft 17. The hub of the pawl or detent is formed or provided adjacent to the support 7 with a cam 20, adapted by engagement therewith to open the switch independently of the spring 10, as hereinafter explained, in case the spring is broken or fails to act.

A curved switch operating member 22, forked or recessed to straddle the pawl or detent 18, is fixed on the rocker shaft 17 and is 90 adapted to engage at the ends with the lugs or projections 12 and 19 for closing the switch and for disengaging the pawl 18 from the shoulder 11 and releasing the pivot support 7 of the contact springs 6. 95

A spring 23, fastened to the member 22, tends to hold the pawl 18 against the hub of the pivoted support 7 and in engagement with the shoulder 11.

The rocker shaft 17 is provided outside 100 of the case 1 with means adapted to cooperate with a part of the crane or hoist for releasing the limit switch and stopping the motor when the hook block or sheave of the hoist is lifted to a certain point and for 105 closing the switch and automatically restoring the hoisting circuit of the motor when the hook block or sheave is lowered

from such point. For this purpose a weighted or gravity arm 25, fastened to one end of the shaft 17 outside of the case 1, and tending normally to turn the shaft in a clockwise direction and to hold the member 22 in engagement with the lug or projection 12, is shown in Figs. 1 and 3.

The contact springs 6 are electrically connected with each other by a metal plate or bar 27, and the contact blocks or pieces 4 are connected by wires 28 with a shunt or branch 29 from the hoisting circuit 30 of the motor, as shown by the diagram, Fig. 3. The shunt or branch 29 includes the coil of a solenoid or magnetic cut-out 32, which is in and controls the circuit 30. The armature and field of the hoisting motor are designated in Fig. 3, *a* and *f* respectively.

The safety-limit switch may be suspended by a bracket or hanger 34, as shown in Fig. 3, from the trolley (not shown) of the crane, or otherwise mounted on a part of the hoist with the weighted or gravity arm 25 extending therefrom, between the runs of the chain or cable *c* by which the hook block or sheave *h* is suspended from the hoisting drum (not shown) of the crane.

In the operation of the safety-limit switch, in case the operator should inadvertently allow the hook block *h* to be lifted above the limit of safety, it will by engagement with the arm 25, turn the rocker shaft 17 with the member 22 fixed thereon, to the left or counterclockwise, as shown in Fig. 2, and the member 22 by engagement with the projection 19 on the pawl 18, will disengage the pawl from the shoulder 11, thereby releasing the pivoted support 7, whereupon the contact springs 6 will be instantly thrown by the snap-action of the spring 10 away from the fixed contact blocks 4, thus automatically breaking the branch circuit through the coil of the solenoid or magnetic cut-out 32, releasing the switch, which opens the hoisting circuit 30 and stops the motor, and leaving the lowering circuit of the motor in operative condition.

As the member 22 is turned to the left and disengages the pawl 18 from the shoulder 11, it is moved away from the projection 12 and allows the switch to open. When the pawl 18 is disengaged from the shoulder 11 and releases the support 7 the projection 12 is brought into engagement with the member 22 which acts as a stop to limit the opening movement of the contact springs 6.

When the hook block *h* is lowered sufficiently to release the arm 25, the weight of the arm turns the rocker shaft 17 with the member 22, back to the right, or clockwise, as shown in Fig. 2, and the member 22 engaging the projection 12, turns the support 7 against the tension of the spring 10, till the contact springs 6 engage with the contact blocks 4, thereby closing the switch and re-

storing the shunt or branch circuit 28 to operative condition at the limit switch, and the pawl 18 engages with the shoulder 11, thereby locking the switch closed. Sufficient play or lost motion is provided between the ends of the member 22 and the projections 12 and 19 when the switch is closed and the pawl 18 is engaged with the shoulder 11, as shown in Fig. 2, to allow for a limited movement of the arm 25 which may result from vibration or shocks of the bridge or part of the crane or hoist to which the limit switch is attached, without disengaging the pawl or detent 18 from the shoulder 11 and thereby accidentally releasing and permitting the switch to open.

Various changes in the construction and arrangement of parts of the limit switch and of its circuit connections with a crane or hoist to which it is applied may be made without materially affecting the principle and mode of operation of the switch and without departure from the invention as defined in the following claims.

I claim:

1. In a safety-limit switch for electric hoists the combination of contact members one of which is movable into and out of engagement with the other, means constantly tending to open the switch, means for releasably holding the switch closed, and means adapted to be actuated by the shifting of a part of a hoist to a certain limit to release said movable contact member, and when said part recedes from said limit, to automatically close the switch.

2. In a safety-limit switch for electric hoists, the combination of contact members one of which is movable into and out of engagement with the other, means constantly tending to shift the movable member out of engagement with the other, a detent for releasably holding the movable member in engagement with the other, and means adapted to be actuated by a movable part of a hoist when it is shifted to a certain limit to disengage the detent and release the movable contact member and to automatically shift said movable contact member back into engagement with the other contact member when said movable part recedes from said limit.

3. In a safety-limit switch for electric hoists the combination of a relatively fixed contact member, a pivotally mounted contact member movable into and out of engagement with the fixed member, means tending to shift the movable member away from the fixed member, a detent for releasably holding the movable member in engagement with the fixed member, an oscillatory switch controlling member normally tending to close the switch, and means connected with said controlling member and adapted to be actuated by a movable part

of a hoist when it is shifted to a certain limit to disengage the detent and release the movable contact member.

4. In a safety-limit switch for electric hoists the combination of a relatively fixed contact member, a pivotally mounted contact member provided with a shoulder and a projection, means tending to shift the pivoted contact member away from the fixed member, a pivoted detent adapted by engagement with the shoulder on the pivoted contact member to releasably hold said member in engagement with the fixed contact member and provided with a projection, and a rocker member mounted coaxially with the detent and adapted when turned in one direction by engagement with the projection on the detent to disengage the detent and release the pivoted contact member, and when turned in the other direction by engagement with the projection on the pivoted contact member to shift said member into engagement with the fixed contact member.
5. In a safety-limit switch for electric hoists the combination of a relatively fixed contact member, a contact member movable into and out of engagement with the fixed member and provided with a shoulder and a projection, means tending to shift the movable contact member away from the fixed member, a detent provided with a projection and adapted by engagement with the shoulder on the pivoted contact member to releasably hold said member in engagement with the fixed contact member, and a controlling member movable with lost motion between the projections on the detent and movable contact member and adapted when shifted in one direction to disengage the detent and release the movable contact member, and when shifted in the other direction to shift the movable contact member into engagement with the fixed contact member.

6. In a safety-limit switch for electric hoists the combination of a relatively fixed contact member, a pivoted contact member provided with a shoulder and a projection, means tending to shift and hold the pivoted member out of engagement with the fixed member, a pivoted detent adapted by engagement with the shoulder on the pivoted contact member to releasably hold said member in engagement with the fixed member and provided with a projection, a rocker member coaxial with the pivot of the detent and adapted to cooperate with the projections on the detent and pivoted contact member, and a gravity member connected with the rocker member and adapted to be actuated by a movable part of a hoist when it is lifted to a certain limit to disengage the detent and release the pivoted contact member and when said movable part descends from said limit to shift the pivoted contact member back into engagement with the fixed member.

7. In a safety-limit switch for electric hoists the combination of a relatively fixed contact member, a pivoted contact member provided with a projection, a pivoted detent adapted by engagement with the pivoted contact member to releasably hold it in engagement with the fixed contact member and provided with a projection, a rocker member adapted when turned in one direction to disengage the detent and release the pivoted contact member, and when turned in the other direction to shift the pivoted contact member back into engagement with the fixed member, and a cam on the detent adapted to force the pivoted contact member away from the fixed member when the detent is disengaged from the pivoted contact member by the rocker member.

In witness whereof I hereunto affix my signature.

MATTHIAS A. BECK.
